United States Patent Office

Des. 187,674
Patented Apr. 12, 1960

187,674

PUMP HOUSING

Ernest E. Cook and Harry J. Sadler, Minneapolis, Minn.

Application December 3, 1959, Serial No. 58,535

Term of patent 14 years

(Cl. D65—1)

Fig. 1 is a view in perspective as seen from one side and end of a pump housing showing our new design;

Fig. 2 is a view in perspective thereof as seen from the opposite side and end from that shown in Fig. 1; and

Fig. 3 is a view thereof in end elevation as seen from the left side of Fig. 1.

We claim:

The ornamental design for a pump housing, as shown.
